(57) **CLAIM**

The ornamental design for a hand cultivator, as shown and described.

DESCRIPTION

FIG. 1 is a top perspective view of a hand cultivator, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a plan view of the enlarged top surface;

FIG. 8 is a plan view of the enlarged bottom surface;

FIG. 9 is a view of FIG. 1, shown in an alternate environment;

FIG. 10 is a view of FIG. 1, shown in a second alternate environment; and,

FIG. 11 is an enlarged detail view of area 11 in FIG. 1. The broken lines in the drawings illustrate the portions of the hand cultivator, which form no part of the claimed design. The dash-dot-dash broken lines encircling the enlarged views are for annotative purposes only and form no part of the claim thereof.
